CLOTHES PIN HOLDER

Lester Cohen, Syracuse, N. Y.

Application March 21, 1956, Serial No. 40,710

Term of patent 7 years

(Cl. D58—26)

The single figure is a perspective view of a clothes pin holder showing my design.

The sides of the holder not shown are the same as the sides shown. The characteristic features of my design for a clothes pin holder reside in the configuration of the supporting handle as shown.

I claim:

The ornamental design for a clothes pin holder, substantially as shown and described.
